UNITED STATES PATENT OFFICE

2,566,894

REEL

Simeon Kaczmarek, Hamburg, N. Y.

Application March 25, 1947, Serial No. 737,188

1 Claim. (Cl. 242—127)

1. My invention relates to reels and more particularly to a reel that may be used to support a skein of yarn or the like.

The object of my invention is to provide a convenient adjustable reel that is equipped with a plurality of projecting arms which may be equally expanded or retrieved with but a single adjustment means.

Another object of my invention is to provide a device of the character described that may be placed on any horizontal surface, and be constructed in a manner so it will occupy a minimum of space when stored.

A further object of my invention is to provide a device that will revolve with a minimum amount of frictional resistance and may be actuated in a rotary fashion by a pulling action on the yarn being removed from the skein disposed thereon.

A still further object of my invention is to provide a device that is economical to construct, easy to operate and adjust, one that is efficient in performing the function for which it is intended.

It is manifest to anyone familiar with yarn or the like that the product is put up in skeins of various sizes and it is my intention to provide a device that may be easily adjusted for supporting any size of skein of yarn or the like, so as to permit the yarn to be relayed from the skein arrangement to a ball or the like for use.

Other and further objects of my invention will become more apparent as the description proceeds and when taken in conjunction with the drawing in which

Figure 1 is a perspective view of the assembled device showing the projecting arms in a retrieved or folded position.

Figure 2 is a fragmentary cross-sectional view of the upper portion of the vertical standard.

Figure 3 is a perspective view of the assembled device as shown in Figure 1, showing the projecting arms in an expanded position, and

Figure 4 is a fragmentary cross-sectional view of the lower portion of the vertical standard in its relation with the base and lower hinge plate.

Similar characters of reference indicate corresponding parts throughout the several views, and referring now to the same, the device is provided with a base shown as 10 which is arranged for placing on any horizontal surface. Obviously, the device may also be supported by a clamp, the arrangement of the mounting does not in any way effect its operativeness. There is a vertical stem or standard shown as 11 which is shown having an upper thread 12 and a lower thread

13. The lower thread 13 of the vertical stem 11 is threadedly engaged into a lower hinge plate shown as 14. This hinge plate 14 is provided with a plurality of sockets 15 around its peripheral edge and these sockets 15 are arranged to accommodate adjustment links shown as 16 and which are hingedly attached to the lower hinge plate 14 by means of pins shown as 17.

The lower hinge plate 14 is further provided with a downwardly extending member having a conical lower portion 19 and recessed to accommodate a ball 20 which acts as a support for the lower hinge plate 14 when it is inserted into an aperture 21 disposed within the base 10 and the bottom of this aperture 21 is provided with a recess of semi-radial contour to accommodate the lower portion of the spherical member or ball 20.

The hinge plate 14 is also supported in a vertical position by means of a ball bearing assembly 22 which is disposed within the upper portion of the base 10 and which is retained in position by means of a radial plate shown as 23 which is attached to the base 10 and held in position by means of the screws shown as 24. The inner member of the ball bearing assembly 22 engages the extending face 25 of the lower hinge plate 14 and thus the plate 14 is supported in a horizontal and vertical position by means of the ball bearing assembly 22 and the spherical ball 20 respectively.

The upper portion of the vertical standard or rod 11 engages an upper hinge plate shown as 26 also provided with a plurality of recesses or sockets 27 into which the adjustable links 16 are placed and hingedly supported by means of pins 17. The upper portion of the upper hinge plate 26 is provided with an extending member 28 which has a radial groove shown as 29 around its entire peripheral surface.

The vertical standard 11 is also provided with a threadedly engaged hollow adjustment nut shown as 30 which is provided with a downwardly disposed collar 31 into which the screws 32 are inserted and the ends 33 of the screws 32 engage the radial slot 29 in the upper portion 28 of the upper hinge plate 26 to retain the hollow adjustment nut 30 in rotatable engagement with the upper hinge plate 26 at all times and permit the upper hinge plate 26 to remain in position where it does not rotate on the vertical standard 11 when the hollow adjustment nut 30 is turned by means of the operator engaging the knurled surface of the nut 30. The revolving of the hollow adjustment nut 30 will

cause the upper hinge plate 26 to be raised or lowered on the vertical standard 11. The adjustable links 16 in their pivoted action force the contact member shown as 34 toward and away from the vertical standard 11. Obviously, the contact members 34 are provided with a hinged support at 35 onto one of the end adjustment links 16 while the lower end of the contact members 34 are provided with an engaging slot shown as 36 which permits the slidable movement of the pin 37 on the lower end of the adjustable link 16.

With the arrangement as shown, skeins of yarn or the like of various sizes may be placed onto the contact members 34 and the adjustment and 15 rotary movement of the hollow adjustment nut 30 will cause the projecting arms to extend outward at all points so that the yarn can be suspended with any pre-determined amount of tension.

It is also obvious that any number of extending or projecting arms may be employed and the device may be constructed to accommodate any number or size of these projecting members.

While I have shown a specific arrangement of the component parts constituting the device, I am fully cognizant of the fact that many changes in their form and configuration may be made without in any way effecting their operativeness and efficiency, and I reserve the right to make 30 such changes as I may deem necessary or convenient without departing from the spirit of my invention or the scope of the appended claim.

Having thus described my invention, what I claim and desire to secure by Letters Patent in 35 the United States is:

A device of the character described comprising a base, a vertical standard rotatably supported by said base, a lower hinge member forming a part of said vertical standard, an upper hinge member provided with an extension having a radial groove, slidably supported by said vertical 40 standard, a hollow adjustment nut threadedly engaging the upper ends of said standard, said

nut provided with a downwardly disposed collar, said collar provided with a plurality of apertures, said collar journaled on said extension, fastening elements, said fastening elements adapted for insertion in said apertures and said groove for holding said collar on said extension, said nut employed for slidably moving said upper hinge member toward or from said lower hinge member, support arms comprising a plurality of link members hingedly attached at their central portion and ends to one another, the ends of a pair of said link members hingedly attached to said hinge plates, contact members hingedly attached at their upper end to the depending end of one of said link members, said contact members provided with elongated slots at their lower end for hingedly engaging the lower depending end of one of said links, thereby causing the angle of said link members to change when 20 said nut is moved on said standard causing said contact members to move toward and away from said vertical standard, said lower hinge plate having a reduced extension cone-shaped at its free end, said end provided with a recess, a ball bearing assembly, a spherical ball, said assembly disposed within said base and supporting the upper part of said extension, said ball disposed in said recess and said base.

SIMEON KACZMAREK.
